UNITED STATES PATENT OFFICE.

EARLE WILLIAMSON, OF CHICAGO, ILLINOIS.

TEMPORARY TYPE-PAGE LOCK.

Application filed March 5, 1927. Serial No. 173,019.

This invention relates to temporary form frames for holding type pages and the like.

The principal object of the invention is the provision of a new and improved form lock for temporarily locking forms or type pages and the like.

Another object of the invention is the provision of a new and improved locking means for forms, type pages and the like that is resiliently held in locked position and may be readily detached.

A still further object of the invention is the provision of a temporary form frame with new and improved means for holding the frame and type page in assembled relation, of such a nature that it may be locked in a permanent form without removing said locking means.

Other objects of the invention are the provision of a temporary form frame with new and improved means for locking or securing the parts of said frame in position, that is simple in construction, cheap to manufacture, easily assembled, and one that permits 25 pages to be justified and the temporary frame locked in position in a minimum amount of time.

Other and further objects and advantages of the invention will appear from the following description taken from the accompanying drawings, in which

Fig. 1 is a plan view of a type page or form, showing the invention in position around the same, with parts broken away and parts in section;

Fig. 2 is a perspective view of one of the sections of the frame;

Fig. 3 is a perspective view of the locking member;

Fig. 4 is a perspective view of a modified form of the device, showing the same in position on the type page or form;

Fig. 5 is a perspective view of a modified form of the locking device;

Fig. 6 is a plan view of a portion of a type page showing a modified form of frame and locking means, with parts in section;

Fig. 7 is a plan view of a type page showing a further modified form of the device;

Fig. 8 is a section on line 8—8 of Fig. 7;

Fig. 9 is a plan view of a type page or form showing a still further modified form of the frame and locking member;

Fig. 10 is a section on line 10—10 of Fig. 9; and

Fig. 11 is a perspective view of a still further modified form of the locking device.

In printing, it is the common practice to temporarily tie up type or slug pages for proofing and the like. This usually is done by winding a string about the type pages to hold the type in assembled relation. This method is not only cumbersome but requires a great amount of time to wind and unwind the string where justifying, correcting and the like are necessary. It has also been proposed to employ a frame in which the sides and ends are interlocked, but the type page cannot be clamped for firmly holding the type, slugs, etc. together without the use of a wedge which necessitates the use of a special tool for removing the same in order to loosen the frame for justifying, correcting and the like.

The present invention seeks to eliminate these difficulties by providing a frame and lock that may be applied and removed in a fraction of the time usually employed for this purpose.

On the drawing, the reference character 80 10 designates a type page, the individual parts of which are held assembled by a frame 11 of any suitable material. In the form of the device selected to illustrate one embodiment of the invention, the frame is of metal. 85 But whatever be the nature of the material used, it is desirable that a groove or channel be provided in the outer surface of each section of the frame for receiving and protecting the temporary locking means. 90

The frame comprises a plurality of independent sections. In the form of the device shown in Fig. 1 the frame is rectangular and comprises the side members 13 and upper and lower or end members 14. The side 95 members are provided with grooves or channels 15, and the end members 14 with grooves or channels 20, on their outer sides, for receiving the resilient locking members 16 for holding the frame members assembled. 100 The corners are mitered as at 17 whereby the groove or channel 15 will be continuous about the frame.

Means are provided for clamping the sections of the frame together. Preferably 105 this means comprises U-shaped locking members 16 extending about opposite ends or sides of the frame and having their ends interlocked with the adjacent frame members. As shown, the locking members 16 are 110

provided with resilient tongues 19 for engaging openings or notches 18 in the frame sections 13.

The locking members 16 each comprises a resilient body portion 21 having its ends 22 bent to extend at acute angles to the body portion, whereby the resiliency of the end portions 22 will force the side members inwardly to clamp the ends of the type lines or slugs. The body portion 21 is bowed inwardly at its central portion for engaging the bottom walls of the grooves or channels 20 as clearly shown in Fig. 1, for forcing the end members inwardly to clamp the type. The ends 22 terminate in outwardly extending portions 23 which constitute finger pieces for releasing the locks.

In locking the frame in position on the type page or form, the side and end members 13 and 14 are placed in position at the sides and ends of the type page, respectively, the locking member is then placed in the channels or grooves 20 in the end members, after which the ends of the locking members are forced inwardly along the channels 15 of the side members until the tongues 19 snap into the recesses 18, thereby placing the curved body portion and the curved connections between the body portion and end portions under tension. The type page or form is now temporarily locked, with the frame members clamping the type or slugs, the ends of the locking member forcing the side members of the frame inwardly, and the bowed or curved portion of the lock forcing the end members inwardly for clamping the type or slugs.

It will be noted that by mitering the ends of the frame members the grooves 15 are continuous with the grooves 20 about the corners formed by said members. When the lock is in position, as shown in Fig. 1, it will be noted that it is entirely protected by the outer edges of the frame members, so that the page or section of a page may be locked in the form without interfering in any way with the temporary locking member.

In order that the same locking member may be used for different lengths of frame members, the same may, if desired, be made adjustable as to length. Any suitable means may be employed for effecting this adjustment. As shown in Fig. 3 the body portion 21 is divided into two sections 24 and 25 which are adapted to overlap each other at their central portion. One of the sections, as 25, is provided with lugs 26 bent laterally and then inwardly to form a channel for receiving the section 24. The section 25 is provided with a plurality of recesses 27 which are adapted to be engaged by an inwardly extending lug 28 on the inner end of the section 24. By moving the outer end of the section 25 outwardly the lug 28 may

be disengaged from the apertures 27 and the parts slid to adjusted position. By means of this arrangement the lock may be adjusted to various sizes of frames.

The form of the device shown in Fig. 4 ⁷⁰ differs from that described above in that the locking member 160 is attached to the upper and lower sections 140 of the frame instead of the side members 130 thereof. The locking member 160 differs from that ⁷⁵ described above in that it is made from a single strip of spring metal.

The form of the device shown in Fig. 6 differs from that shown in Fig. 4 in that the corners of the frame members 31 and 32 ⁸⁰ are not mitered. The end members, or upper and lower sections 31 of the frame are of the same length as the width of the page. In other words, the ends of the side members 32 are flush with the outer surface ⁸⁵ of the top and bottom sections 31. In order that the groove 33 in the side member 32 and the groove 34 in the end members 31 be continuous about the corners the bottom wall of the groove 32 is removed for a space ⁹⁰ equal to the depth of the groove 34 as shown at 25 in Fig. 6.

In the form of the device shown in Fig. 7 only top and bottom frame members 36 and 37 are employed. The ends of the type ⁹⁵ slug lines 38 are channeled as at 39 and 41 for receiving the resilient locking members 42 and 43 as indicated in dotted lines in Fig. 7. This form of the device can only be used when the entire page or section of a ¹⁰⁰ page is made up of slug lines.

In the form of the device shown in Fig. 9 only side members 44 and 45 are employed. The resilient locking members 46 which are of the same form as 160 shown in Fig. 5 ¹⁰⁵ extend across the top and bottom of the type page or form and are secured in channels of the side members 44 and 45 in the same manner as that disclosed in Fig. 1. In order to protect the body portion of the ¹¹⁰ spring member 46 when the page is locked in the permanent form, channel members 47 and 48 may be placed over said spring members for protecting the same, as clearly shown in Fig. 10.

In the form of locking member shown in Fig. 11 the body portion comprises the two sections 51 and 52 slidably connected together with means for automatically locking the same in adjusted position. As shown, the inner ends of the sections are provided with projections 53 and 54 bent laterally and then inwardly for slidably engaging over the edge of the cooperating sections 51 and 52, respectively, one of the sections, as the section 52 being provided with a resilient tongue 55 for snapping into corrugations 56 formed in the member 51, for holding the sections in adjusted position. The body portion is preferably curved ¹²⁰

as at 56 as in the devices described above, although this is not necessary as the curves 57 and 58 at the junction of the body portion and laterally extending arms will be placed under tension when the device is applied.

In all forms of the device the locking member is in the form of a resilient U-shaped element preferably having its ends a less distance apart than the dimension of the frame to which it is attached whereby the spreading of the ends will cause the same to clamp the frame. The central portion of the member in all cases is preferably curved or bowed inwardly so that in attaching this member it is particularly straightened, thereby pressing inwardly on the section engaged by it. When the locking members are attached to the form frame they will therefore resiliently press inwardly on all sections of the frame for clamping the type page.

While I have shown the interlocking connection between the locking members and the adjacent frame sections as comprising resilient tongues on said members engaging in notches or recesses in the frame members, it is understood that any suitable interlocking connection may be employed. It is only necessary that the locking members be so connected to the frame sections that they will tend to firmly hold said sections in contact with the page or section of a page which it embraces.

If desired the frame members may be cut as occasion for their use arises, in which event they are cut the desired length from stock, and the holes or notches made by special tools supplied to the users. The resilient locking member 16 may be adjusted as described above to accommodate frames of different sizes.

It is understood that the term "type lines" as used in the specification is intended to include individual type, spaces, slugs and the like, and that the term "type page" includes individual type, slug type spaces, quadrats, slugs, cuts and the like that are used in printing to compose a page or section of a page, as the case may be.

It is thought from the foregoing taken in connection with the accompanying drawings that the construction and operation of my device will be apparent to those skilled in the art, and that various changes in size, shape, proportion and details of construction may be made without departing from the spirit and scope of the appended claims.

I claim as my invention:

1. A frame for temporarily locking type pages and the like which comprises a plurality of frame sections for enclosing a type page, a pair of U-shaped spring members for extending about opposite sections of said frame and having their ends interlocked

with the remaining sections of said frame for holding said sections in assembled relation.

2. A frame for temporarily locking type pages comprising a rectangular frame having sides and end sections provided with mitered corners, the outer surface of each section being provided with a channel, each side section being provided with recesses, a U-shaped spring locking member engaging in said channels and having projections at each end for engaging in said recesses for holding said locking member in position and said frames in assembled relation.

3. A locking member of resilient material for frames for type pages and the like comprising a curved body portion having laterally extending ends, said ends converging and each being provided adjacent its extremity with resilient tongues extending convergingly toward said body portion for forming retaining projections for said members.

4. A frame for temporarily locking type pages and the like, comprising side and end sections arranged in the form of a rectangle, said end sections extending across the ends of said side sections, said frame being provided with a continuous groove extending about its outer periphery, the outer ends of the side sections of said frame being provided with notches spaced from the ends thereof, and resilient locking members having body portions engaging in the grooves in said end members and having end portions provided with retaining projections for engaging said notches, said end portions being bent outwardly to form finger pieces for releasing said locking members.

5. A frame for temporarily holding type pages and the like, comprising end and side sections, and a locking member of resilient material having a body portion for engaging in a recess in one of said sections and having angular ends for engaging recesses in adjacent sections, said ends being provided with projections for engaging notches in the ends of said adjacent sections, said body portion being normally curved inward and said ends normally converging, whereby when said locking member is applied to said frame all of said sections engaged thereby will be forced inwardly by said locking member.

6. A frame for holding type pages and the like, comprising end and side sections, a locking member extending about each end section of the frame and having its ends engaging the side sections for drawing the end sections toward said side sections.

7. A frame for temporarily holding a type page, comprising rigid frame sections at opposite sides of said type page, U-shaped spring clips extending across opposite sides of said type page, and interlocking means

for connecting the ends of said clips with said frame sections for holding said type page in assembled relation.

8. In a frame for temporarily holding a type page, rigid frame members for engaging opposite sides of a type page, U-shaped spring clips extending across opposite sides of said type page, interlocking means for connecting the ends of said clips with said frame sections for holding said type page in assembled relation, and means whereby said clips may be adjusted to lengthen or shorten the same.

9. A locking member for frames for type

pages and the like, comprising an inwardly curved resilient body portion, laterally extending resilient arms carried by said body portion, said arms converging in the direction in which said body portion is curved, and means on the outer ends of said arms for interlocking with type page frame members whereby when a plurality of said clips are applied to a type page the latter will be clamped longitudinally and transversely by the resiliency of said arms and body portion.

In testimony whereof I affix my signature.
EARLE WILLIAMSON.
